ATTORNEY

UNITED STATES PATENT OFFICE

GEORGE J. COLLINS, OF NEW YORK, N. Y.

HAT PROTECTOR

Application filed May 13, 1931. Serial No. 537,122.

This invention relates to hat protectors intended to protect hats from rain and so forth.

The hat protector of my invention is pri-

5 marily intended to be used on men's straw hats although it may be used on women's straw hats and also on men's and women's hats of other material.

One of the objects of my invention is the 10 provision of a hat protector which may be compactly folded and carried in a pocket.

Another object of my invention is the provision of a hat protector provided with 15 means for securing the same to a hat, said securing means being invisible to an observer when the protector is applied to a hat.

A further object of the invention is the provision of a hat protector embodying 20 means for securing the same to a hat, the securing means being readily attachable and detachable and adapted to use in various ways as hereinafter pointed out.

A still further object of the invention is the provision of special reinforcing means 25 for the hat protector, which is preferably made of thin water-proof material.

Another object of the invention is the provision of a hat protector of exceptionally neat appearance and graceful lines.

30 Other objects will be appreciated from a reading of the following specification.

The invention will be fully and comprehensively understood from a consideration of the following detailed description when 35 read in connection with the accompanying drawing which forms part of the application, with the understanding, however, that the improvement is capable of extended application and is not confined to the exact showing of the drawing nor to the precise construction described and, therefore, such changes and modifications may be made therefrom as do not affect the spirit of the 40 invention nor exceed the scope thereof as expressed in the appended claims.

In the drawing:

Fig. 1 is a perspective view showing a man 45 wearing a straw hat to which the protector of my invention is attached.

Fig. 2 is a perspective view of the hat protector itself.

Fig. 3 is a broken plan view of the hat protector.

Fig. 4 is a fragmentary sectional view of a 55 straw hat of the conventional type showing the method of attaching certain flexible means employed in my hat protector to the straw hat; and

Fig. 5 is an enlarged section taken on line 60 5-5 of Fig. 3, looking in the direction of the arrows.

Referring to the drawing for a more detailed description thereof, the hat protector of my invention is preferably made from a 65 substantially circular piece of waterproof material, such material being for example a vegetable parchment available for purchase. The circular sheet is provided, as illustrated in Fig. 3, with four plaits indicated by the 70 numeral 7, these plaits being radially disposed and extending from the periphery of the sheet to points near the center of the same. These plaits give a concavo-convex form to said circular sheet whereby the sheet 75 is adapted to go over the crown and the brim of a hat. Said plaits also serve to strengthen the sheet so that flexible means hereinafter mentioned for attaching the protector to a hat are preferably secured to the protector at 80 these strengthened portions.

Folded reinforcing members 9 fit over the inside tucks or folds 7a of the plaits 7 in order to further strengthen the plaited portions of the protector. The reinforcements 9 are 85 tapered to conform to the plaits and in addition to their reinforcing function serve to give a better flare to the hat protector at and adjacent the rim thereof. Tapes 10 are secured to the hat protector, said tapes passing 90 through the reinforcing members 9 and through the plaits to the outside of the hat protector where they engage retaining means 12. Said tapes are secured to the hat protector at points above the line of contact of the 95 protector with the brim of the hat so that any tension on the tapes will not be effective to press the hat protector against the edge of the hat brim. The tapes are made in crossing loops, loosely secured together at the points 100

of closing by looped cord or tape, as indicated at 15 in Fig. 2, this to maintain the general relation of the tapes but to permit them being easily slid one with reference to the other.

5 The tapes extend into the hat at the crown to rest upon the head of the wearer. The loop 15 may be omitted without affecting the function of the tapes.

Slidably mounted on but frictionally engaged with each tape is a disc 17, the lower portions of said discs being adapted to be placed between a sweatband 19 of a hat 20 and the inner surface of the crown of the hat, thereby to hold the tapes and therefore the hat protector to the hat.

10 While the discs 17 adjustably mounted on the tapes make for more effective mounting of the protector, they are not absolutely essential to its proper function, as the placement of the tapes within the crown of the hat, after the protector has been attached, the tape being then pressed against the sides of the crown by the head of the wearer, insures the retention of a protector in place.

15 25 What I claim as new is:

1. A device for the purpose indicated comprising a protector stamped from sheet material and arranged into concavo-convex form to cover the crown and brim of a hat, attaching tapes secured to the protector at spaced points therearound and adapted to pass under the brim and into the crown of the hat, and members attached to the tapes and engageable with the sweatband, said members lying flat against the inner face of the crown of the hat and tensioning the tapes to secure the protector to the hat and permit the latter's removal from the head without disarrangement of the tapes.

20 40 2. A device for the purpose indicated comprising a protector stamped from sheet material and arranged into concavo-convex form to cover the crown and brim of a hat, attaching tapes secured to the protector at spaced points therearound and adapted to pass under the brim and into the crown of the hat, and members attached to the tapes and engageable with the sweatband, said members lying flat against the inner face of the crown of the hat and tensioning the tapes to secure the protector to the hat and permit the latter's removal from the head without disarrangement of the tapes.

45 50 55 55 In testimony whereof I hereby affix my signature.

60 GEO. J. COLLINS.
